UNITED STATES PATENT OFFICE

JOHN P. MCCLIMANS, OF DULUTH, MINNESOTA

METHOD OF SUPPORTING, CONSTRUCTING, AND REPAIRING FURNACE ROOFS

Application filed June 25, 1927. Serial No. 201,487.

The invention pertains to furnace roofs and more particularly to a method of construction or repair of roofs of furnaces of the open hearth type.

5 In the operation of open hearth furnaces, the roof generally erodes most rapidly directly above the tap hole of the furnace due to flying molten metal. It is necessary and highly desirable that these eroded areas be 10 repaired while the furnace is in operation due to the fact that it is very expensive to have to discontinue the use of a furnace while it is cooled and repaired. Formerly it has been the practice, in fact it has been necessary, to discontinue the use of a furnace, cool 15 it down and then have the carpenters erect on the inside an expensive scaffolding for the repair of this eroded part.

It is therefore an object of this invention 20 to provide a simple, inexpensive and effective method of repairing an open hearth furnace roof without necessarily cooling down said furnace.

25 Another object is to provide a method of repairing furnace roofs wherein the work may be wholly conducted externally of the furnace.

Still another object is to provide a method 30 to be used in repairing furnace roofs whereby the part of said roof to be repaired is built up sectionally.

Other and further objects will readily occur from the detailed description, claims and drawings appended hereto.

35 In the drawings, wherein like reference characters are used to designate like parts—

Fig. 1 is a perspective of a part of the roof and adjacent wall of a furnace of the open hearth type, illustrating the use of the device 40 for repairing an eroded portion of the roof;

Figure 2 is a vertical section illustrating the procedure in repairing an eroded area; and

45 Figure 3 is a perspective of one of the bricks with its attaching handle for supporting the brick in place from a part of the device.

The usual open hearth furnace comprising 50 a vertical wall 10 and the roof 12 is shown having a roof built up in the form of a cor-

rugated surface formed of bricks 13 and 14, the object being to provide a greater radiating surface on the upper side of the arched roof for the purpose of carrying away the heat received by the arch from the molten 55 metal and also to reduce the expense of maintaining the arch by use of standard brick shapes. As already pointed out, usually above the tap hole an erosion takes place, as indicated by the dotted line 15 of Figure 1. 60 In order to repair this damaged area, the eroded part is squared up for the reception of the usual standard bricks 18. A strip of metal 16 having a supporting foot 17 is then 65 laid on top of the arch, the foot portion resting on top of the side wall and the remainder thereof completely spanning the hole. The bricks 18 are then indented or apertured at 19 by any convenient means, as a pick, and 70 may be done by workmen in the process of repairing the roof. The wire handle 20, which is in the form of a loop and provided with prongs, is then fastened to said brick by inserting the prongs into the indentations 75 and it will be noticed that the handle on the side of the brick to be placed nearest the metal strip is offset from the side of the brick to form a shoulder 21. The brick is then slid into place resting on the skewblock and is 80 prevented from sliding down into the furnace by frictional engagement with the other parts of the roof and also by reason of the shoulder 21 resting on the metal strip 16. Other bricks are then slid into place enough to fill 85 one row or course at that particular point until the last brick 22 is reached. This brick performs the function of a key-brick and need not be provided with handles as it is used to wedge that course of bricks in position. When this brick is finally reached, the 90 spring handles 20 may be pulled from their attachment and the metal strip may then be moved along to accommodate other successive courses of bricks, it being understood 95 that this process is repeated until the hole is completely filled.

In repairing a roof, it is not necessary to maintain the grooved or corrugated surface. This is readily shown by Figure 2 wherein 13 and 14 represent the corrugated original 100

surface of the roof and 18 represents the bricks supplied by this process and the dotted lines 23 represent the courses of bricks to be added to complete the hole.

- 5 It will be readily understood that other and various embodiments of the invention will be apparent to those skilled in the art and I do not wish to be limited by the exact embodiment shown, which it will be appreciated, is merely by way of illustration and not limitation.

I claim:

1. The method of repairing roofs which includes providing a movable member for 15 guiding and supporting a course of bricks, placing a course of bricks, supporting same by the edge of said member and by frictional contact with adjacent roof structure, and 20 placing a key brick to relieve the member of supporting function.
2. The method of repairing roofs which includes placing a row of bricks having removable handles each provided with a shoulder, successively supporting each shoulder on 25 a member provided beside each row, and placing a key brick to relieve said member from supporting said bricks.
3. The method of repairing a furnace roof which includes squaring the hole to be repaired laying a course of bricks successively, each being provided with a handle having a shoulder for supporting each brick on a movable member provided alongside the course, and placing a key brick between the end brick 30 and the furnace structure to relieve the member from supporting relation with said bricks and allowing the handles to be removed.
4. The method of forming arches which includes supporting the units constituting a 40 course of material from a movable member until said course is completed, and successively forming other courses, supporting the same from an adjacent course and said movable member until said last-named courses are completed.
5. An apparatus for use in repairing furnace roofs comprising, in combination, a brace adapted to span the roof, said brace being of a shape conforming substantially 50 to the roof to be repaired, and a plurality of loop shaped members having inwardly extending end portions arranged to engage within the side walls of bricks forming the repair course, said members being provided 55 with shoulder portions for engaging the brace whereby the bricks are supported during the repair operation.

Signed at Duluth, Minnesota, this 20th day of June, 1927.

JOHN P. McLIMANS.
